INVENTOR

James Pullar
BY
Arthur G. Rankin,
ATTORNEY.

UNITED STATES PATENT OFFICE.

JAMES PULLAR, OF HARTFORD, CONNECTICUT.

REFUSE-COLLECTING WAGON.

Application filed September 10, 1920. Serial No. 409,306.

To all whom it may concern:

Be it known that I, JAMES PULLAR, a citizen of the United States, and a resident of Hartford, in the county of Hartford and 5 State of Connecticut, have invented a new and Improved Refuse-Collecting Wagon, of which the following is a specification.

This invention relates to the class of wagons for collecting ashes and other waste 10 material that is required to be removed from more or less thickly populated districts, and an object of the invention, among others, is to provide a device of this kind that shall enable the collection of refuse material to 15 be carried out in a particularly convenient and efficient manner.

One form of refuse collecting vehicle embodying this invention, and in the construction and use of which the objects herein set 20 out, as well as others, may be attained, is illustrated in the accompanying drawings, in which—

Figure 1 is a side view of a wagon embodying this invention and with the elevator trays in their uppermost or discharging 25 positions.

Figure 2 is a similar view with the elevator trays in their lowermost or receiving positions.

Figure 3 is a view in cross section through 30 the wagon as shown in Figure 2.

Figure 4 is a rear end view of the wagon as shown in Figure 1.

The wagon body may be constructed in 35 any convenient manner, and of any suitable material, and for this reason small details are omitted from the drawings herein, such body being shown as formed from a single piece of material, as metal, which body 5 may be of generally rectangular shape in cross section with outwardly flaring sides 6 and with ends 7 conforming in shape to that of the body and flaring sides and sloping upwardly to a peak at the crosswise center. A ridge 8 extends lengthwise of the body, between and supported on the ends, 40 providing openings 9 at the sides of the peak, through which openings material may be dumped into the wagon. The body may 45 be supported in any suitable manner on wheels 10 and any form of motive power may be employed, the device thus far described being of well known and common construction.

55 In the use of such old type of wagon it

has been common practice to manually lift the barrels, cans or other receptacles and throw them through the openings 9, two men being required to lift the receptacles, and a third man being required to empty them in the 60 wagon. With the use of the improved device herein illustrated and described this heavy labor is not required and two men may do the work of the three men above described, this improved wagon including an 65 elevator tray 11 arranged to be positioned low enough to enable a barrel 12 or other receptacle to be tipped from a sidewalk 13 and its contents to be emptied into the tray, that has means for elevating it and for 70 dumping its contents through the openings 9 into the wagon.

This improved device in the form employed herein for disclosing the invention embodies tray guides and supports in the form of rods secured at their opposite ends to the sides of the structure and bent to form supporting loops 14 at their lower ends and vertical guides 15 to receive eyes 16 secured to the backs of the trays. Rests 17 in the form of rods each bent to the desired shape and each secured at its ends to the sides of the wagon body are located to support the trays in their lowermost positions at a suitable distance from said body. Studs 18 project from opposite ends of each tray and elevating cables 19 are secured at their ends to said studs and at their opposite ends are wound about elevating shafts 20 rotatably mounted in the ends 7 and connected by 90 sprockets and chains with operating shafts having crank handles 22 by means of which the loaded trays may be raised, in which operation the eyes 16 will be moved into contact with stops 23 formed by bends at the upper ends of the guides 15, after which a continued pull on the cables 19 as by means of the handles 22 will turn the trays upside down into the openings 9 thereby dumping the contents into the wagon or receiver. It 95 should be noticed that in this elevated and inverted position each tray comprises a cover or closure for an opening 9.

Each tray is provided at its end with a cover removing plate 24 to receive the pressure of a cover removing stud 25 at the end of a cover removing arm 26 secured to a cover removing shaft 27, there being two of these shafts, in the construction herein shown, operated as by means of cover remov- 100 105 110

ing handles 28 located outside of the ends of the wagon body or receiver. By operation of the handles 28, the arms 26 are swung to lift the trays out of the openings 9 and place them in position for the action of gravity to lower them.

I claim—

1. In combination with a wagon body closed on all sides but open at the top for substantially its whole length, a shallow tray closed on all sides but open at the top, means for supporting the tray in a lowered position for the emptying of refuse thereinto from receptacles at different points along its length and dumped from said receptacles by tipping them over the upper edge of said tray, and means for raising the tray and for inverting it over the top of said wagon body to dump said refuse into said body along its whole length.

2. In combination with a wagon body closed on all sides but open at the top for substantially its whole length, a shallow tray closed on all sides but open at the top, means for supporting the tray horizontally in a lowered position for emptying thereinto from receptacles at different points along its entire length of refuse dumped from said receptacles by tipping them over the upper edge of said tray, and means for raising said receptacle and for inverting it at the top of the body to dump the contents into said body.

3. In combination with a wagon body closed on all sides but open at the top for substantially its whole length, a shallow

tray closed on all sides and open at the top and of a shape and size to fit and close the opening into said wagon body, means for supporting the tray in a lowered position for the emptying thereinto from receptacles at different points along its entire length of refuse dumped from said receptacles by tipping them over the upper edge of said tray, and means for raising the tray and for inverting it into said opening in the wagon body.

4. In combination with a wagon body closed on all sides and open at the top, a shallow tray closed on all sides but open at the top, vertical guides located at opposite ends of the tray to guide its vertical movement, rests in the form of brackets projecting from the wagon body to receive the back of the tray and support it in its horizontal position, and means for raising the tray along said guides and for inverting it at the top of the wagon body.

5. A refuse collecting wagon comprising a body, a tray, guide rods secured at their ends to the body and projecting away from the body at their lower ends forming bends to limit and support the tray in its lowermost position, and means for raising the tray.

6. A refuse collecting wagon comprising a body, a tray, guide rods at the ends of the tray to direct its vertical movements, supporting bends at the lower ends of said rods, and a back rest for said tray in its lowermost position.

JAMES PULLAR.
